UNITED STATES PATENT OFFICE.

CHARLES H. SAMPSON, OF ROCHESTER, NEW YORK, ASSIGNOR, BY MESNE ASSIGNMENTS, TO TODD PROTECTOGRAPH COMPANY, OF ROCHESTER, NEW YORK, A CORPORATION OF NEW YORK.

PRINTING-MACHINE.

1,305,012.

Specification of Letters Patent. Patented May 27, 1919.

Application filed February 12, 1914. Serial No. 818,389.

To all whom it may concern:

Be it known that I, CHARLES H. SAMPSON, of Rochester, in the county of Monroe and State of New York, have invented a new and 5 useful Improvement in Printing-Machines, which improvement is fully set forth in the following specification, and shown in the accompanying drawings.

The present invention relates to printing 10 machines and more particularly to that type used for protecting commercial paper, an object of the invention being to provide a simple and inexpensive construction which may be used for writing the exact amount in 15 checks, drafts and other commercial papers. A further object of the invention is to provide a construction in which the parts are so arranged that a long sheet of paper containing a number of checks or other com- 20 mercial instruments may be fed through the machine, thus adapting the machine for use by those large business concerns in which a number of attached checks are signed at one time either by hand or by a duplicating 25 machine.

To these and other ends, the invention consists in certain parts and combinations of parts all of which will be hereinafter described, the novel features being pointed out 30 in the appended claims.

In the drawings:

Figure 1 is a plan view of a printing machine constructed in accordance with the present improvements, the detachable work 35 supporting extensions being shown in position;

Figs. 2 and 3 are detail views of the work support;

Fig. 4 is a vertical section through the ma- 40 chine on the line *a—a*, Fig. 1 showing the gage member shifted from normal position;

Fig. 5 is a horizontal section on the line *b—b*, Fig. 4;

Fig. 6 is a vertical section on the line *c—c*, 45 Fig. 5, showing the normal position of the gage member;

Fig. 7 is a vertical section on the line *d—d*, 50 Fig. 4;

Fig. 8 is a vertical section on the line *e—e*, 55 Fig. 1;

Fig. 9 is a detail view of the operating mechanism for the printing wheel;

Figs. 10 and 11 are two views at right angles to each other, showing one of the inking rollers and its supporting plate removed from the machine;

Fig. 12 is a detail view of the feeding mechanism;

Fig. 13 is a bottom view showing interior parts of the machine; and

Fig. 14 is a section on the line *f—f*, Fig. 4, to show the construction of the work clamp or holder.

According to the illustrated embodiment of the invention, there is employed a main 65 frame preferably made from a single casting and having a base portion 1 supporting an overhanging portion 2 from one side thereof, both being of hollow construction.

Upon the base portion 1, a work support 2 70 is secured preferably to overhang the opposite sides of the base portion 1 and to project slightly from the outer end of said base portion. The work support may have an extension 3 guided thereon so as to project beyond 75 the base 1 for the purpose of increasing the width of the work support to accommodate the paper being operated upon. In this instance, the opposite side edges of the work support are turned downwardly and inwardly at 4 to provide grooves or ways on the under side of the work support for the accommodation of the opposite side edges of the extension 3 which is adapted to operate below the work support 2. The outer 80 edge of the extension 3 is turned upwardly at 5 to provide a gage for the work on the support, said gage extending transversely of the printing line and acting to determine the position of the right hand edge of the check 90 so that the printing line will start at the same point on all the checks.

In order to still further increase the width of the work support, extension plates 100 are employed and are detachably connected 95 to opposite sides of the work support 2. Each extension may have legs or supports 101 depending therefrom near one edge and, near the other edge, tongues or projections 102 may be provided to enter slots 103 in 100 depending lips 104 on opposite sides of the work support 2. The legs 101 are of such length that the plates 100 will be supported in a plane with the work support 2.

The work support may also be provided with a slot 6 through which the platen 7 projects. This platen may be adjustably supported on a cross bar 7^a which is secured by means of screws 8 to lugs 9 on the opposite inner walls of the base 1 as seen in Fig. 8. The adjustment of the platen, in this instance, is in the form of a headed screw 10 which works through an opening 11 in the cross bar 7^a to hold the platen 7 against upward movement. Screws 12 on opposite sides of the screw 10 determine the angular position of the upper face of the platen 7, and a screw 13 journaled on the cross bar 7^a determines the horizontal position of the platen 7.

The printing mechanism is in this instance, in the form of a rotary type wheel or printing member 14 keyed to a shaft 15 which is journaled on a frame 16, the latter being preferably pivoted at 17 at the forward or outer end of the overhanging portion 2. For operating the type wheel 14, the latter may be provided with an integral gear 18 which meshes with the gear wheel 19 arranged on the shaft 20, the latter extending to the outside of the hollow frame 16 and having a handle or grip 21 thereon by which the gear 19 may be turned to position the type wheel 14. An indicator 22 may extend laterally from the shaft 21 to coöperate with characters on a segmental dial frame 23, the characters on this frame corresponding to the printed matter on the type wheel so that, when the pointer coöperates with any one of the characters, the corresponding matter on the type wheel will lie above the platen 7. The matter on the printing wheel consists of words and characters of various lengths sufficient to fill in amounts to be written in checks or other commercial papers, the lines of type being parallel with the axis of turning of the printing member.

The housing or pivoted frame 16 is sufficiently large to inclose the two inking rolls 24, each of the latter being journaled on a swinging frame 25 which is carried by a removable plate 26 forming a portion of the wall of the pivoted frame 16. A spring 27 presses the frame 25 with a roller thereon toward the type wheel 14, and, in order that the roller may be readily removed from the swinging frame 25, the opposite arms of the latter are provided with laterally opening bearing slots 28 in which the ends of the shaft 29^a work. The shaft 29^a is retained in these laterally opening bearings by means of spring arms 29 secured at 30 to the outer faces of the swinging frame and having their free ends provided with pockets 31 which receive the ends of the shaft 29^a.

As the printing mechanism is designed for printing words or other matter and as the length of these words vary, it is desirable to employ a variable work feeding

mechanism in order to obtain the same space between the words. In this instance, the feeding mechanism is in the form of two wheels 32 rigidly secured to a shaft 33 which is journaled on the cross piece 7^a, the wheels 70 operating through openings in the work support 2 on opposite sides of the platen 7. Also rigidly secured to the shaft 33 is a ratchet wheel 34 with which coöperates a spring-pressed pawl 35 that is carried by a swinging arm 36 journaled on the shaft 33. To this swinging arm, a rod or link 37 is eccentrically pivoted at 38. This rod is adjustable at 39 and has its other end eccentrically pivoted at 40 to a swinging frame 41 80 that is mounted to turn about an axis 42 at the rear of the casing below the work support and has an upwardly-extending cam arm or portion 43, lying in a vertical plane with the type wheel shaft 15 so as to coöperate with a gage member or wheel 44 which is arranged upon the shaft 15 at the rear of the work support 2. This gage wheel has a flange extending rearwardly therefrom and provided with an irregular surface forming 90 stop shoulders, the depth of the flange at any one point, corresponding to the length of one of the printed words or characters. In other words, when any character or word is arranged at printing position over the 95 platen, a shoulder or surface on the gage wheel 44 will be arranged to coact with the cam member 43 to effect the shifting of the feeding member a distance corresponding with the length of the word to be printed. 100 Normally, the cam portion 43 projects into the annular flange but does not engage such gage member in order that the latter may rotate relatively to the cam member. When the pivoted frame 16 is moved to effect the 105 printing action, the under side of the arm 43 is engaged by the inner curved face 44^a of the annular flange and the arm is lifted to the position shown in Fig. 4, thus causing the arm 36 to be swung in a direction to carry 110 the pawl 35 over the ratchet wheel 34 without turning the feed wheels 32 and, after the printing action, when the printing wheel and the pivoted frame 16 are returned to normal position under the action of the spring 115 45, the spring 46 shifts the frame 41 and rod 37 to carry the swinging arm 36 in a direction to effect the rotation of the feed wheels 32.

With the end in view of locking the printing wheel against rotation during the printing action, the gage member 44 is provided with a forwardly extending notched flange 48, any one of the notches of said flange being adapted to be registered with a stationary guide member 49 which depends from the casing of the machine at the top of the latter. It is apparent that, when the gage wheel 44 is swung about the pivot 17, one of the notches of this notched flange 48 will 125 130

receive the guide member 49 and hold the printing wheel against rotation during the printing action.

The downward movement of the printing wheel 14 may be determined by a stop 47 preferably in the form of an adjustable screw carried by the overhanging portion of the casing and adapted to coöperate with the upper surface of the shaft 15.

10 A clamping means may also be provided for holding the work with pressure against the feeding member. In this instance, it comprises a frame 50 having bearings 51 on the under side thereof turning on a pivot 15 rod 52 which is supported by a cross piece 53. The latter is rigidly supported at the forward end of the overhanging frame beneath the pivoted frame 16 and carries a spring 54 which bears against the pivoted 20 clamp 50 to press the rollers 55 on the latter, toward the feed rollers 32. For operating the clamp 50, a member 56, pivoted on the pivot 17 of the frame 16, engages the upper surface of the clamp on that side of the 25 pivot opposite the side on which the rollers 55 are mounted. The pivoted operating member 56 has upwardly-extending arms 57 lying on opposite sides of the pivoted frame 16 by which the clamp may be operated.

The operation of the invention will be understood from the foregoing but it may be summarized as follows: A single check or a sheet containing a number of checks is introduced into the machine in a line transverse to the turning axis of the printing wheel. The edge of such check or sheet is brought against the guide flange or gage 5 which is so adjusted that the first matter 30 written by the machine will be positioned near the left hand edge of the check, the gage being so located that the stub of a check may also be attached to such check. For writing a word, the handle 21 is turned 35 until the pointer 22 indicates the proper word on the indicating dial 23, after which the handle is given a movement transverse to its axis of rotation which causes the type wheel 14 and the pivoted frame 16 to turn about the axis 17 in order to carry the type 40 on the type wheel toward the platen 7, the opposing faces of the type wheel and platen being corrugated or roughened in order that the fiber of the paper will be broken at the 45 same time that the printing takes place.

At the time of the adjustment of the printing wheel 14, the variable feed mechanism is set or adjusted to determine the length of the feed after the printing action. This is accomplished through the medium of the gage wheel 44 which rotates with the printing wheel 14 so that the proper stop shoulder will be brought into coöperation with the cam member 43. When the printing wheel is moved toward the platen

7, this gage member shifts the cam member 43 against the action of the spring 46, causing the swinging arm 36 with the pawl thereon to ride over the ratchet 34 without shifting the feed wheels 32. After the handle 31 is released, the pivoted frame 16 returns to its normal position under the action of the spring 45, thus permitting the cam member to move under the action of the spring 46 in order to shift the arm 36 in 75 the opposite direction, and causing the feeding of the check, a distance corresponding to the length of the word printed. This feeding action moves the check inwardly on a line intersecting the supporting portion 80 which connects the base frame 1 with the overhanging frame. After the check has been printed, it is released from the action of the clamp 50 by pressing downwardly on the arms 57, causing the elevation of the 85 rollers 55.

From the foregoing, it will be seen that there has been provided a printing mechanism in which a single rotary hand piece not only positions the type wheel and moves 90 the latter toward the platen, but it also acts to adjust the gage member for determining the feed of a variable work feeding mechanism. The gage member has two movements, one which occurs with the printing 95 member when the latter is adjusted to position the type over the printing point, and the other of which takes place on a relative movement of the printing member and the platen to operate the feed member after the 100 printing operation, the gage member preferably being arranged on a single shaft with the rotary type wheel. It is apparent that this and other features of the invention are not limited to a construction in which the printing wheel moves toward the platen but may be combined in any construction in which a relative movement between a printing member and a platen takes place for 105 effecting the printing operation.

Another feature of the invention is the direction of the feed of the work, that is, in a line which intersects the supporting portion of the main frame which connects the overhanging portion with the base portion. This arrangement is particularly advantageous to large commercial houses and others where the custom is to fill out and sign a number of checks on a large sheet, the particular direction of the feed, herein mentioned, permitting such sheet to be received readily within the machine. In connection with the machine, there is also employed a construction which permits these large sheets to be readily supported. Means is also employed which enables the user of the machine to start all of the checks at a certain definite point, thus securing greater neatness and less liability for the insertion 115 of other matter in advance of the matter 120 125 130

printed, if the latter be begun near the left hand side of the check. This gaging means is adjustable so that the machine may be accommodated to checks of different styles and sizes.

What I claim as my invention and desire to secure by Letters Patent is:

1. In a printing machine, the combination with a platen and a printing member having a plurality of parallel lines of type thereon of different lengths, one of said elements being movable toward and from the other to effect the printing operation, of a gage member having a plurality of rigid shoulders thereon, adjustable with the printing member when the latter is adjusted to position a line of type in printing position, said gage member being movable when the platen and the printing member are relatively moved to effect the printing operation, a feeding member for moving the work between the platen and the printing member, a member having a pawl and ratchet connection with the feeding member, said member being moved in one direction by coöperation with the gage member, and a spring acting on said member in the direction opposite to that which the member is acted on by the gage member.
2. In a printing machine, the combination with a stationary platen, and a printing wheel having a plurality of parallel lines of type thereon of different lengths, of a shaft by which said wheel is carried, said shaft being movable laterally to carry the wheel toward the platen, a gage member having a plurality of shoulders thereon corresponding to the lines of the type on the printing wheel, said gage member being arranged on the shaft to turn with the latter and also to be shifted when the shaft is shifted laterally, and a feed member having its movement controlled by the gage member.
3. In a printing machine, the combination with a platen, a frame pivotally mounted with relation to the platen, a rotary printing member mounted to turn about an axis transverse of the turning axis of the pivoted frame and upon one side of said turning axis, of a variable work-feeding mechanism for moving the work relatively to the platen after each printing operation embodying a feed member and a rotary gage, the rotary gage being mounted on the shaft of the rotary printing member upon the side of the axis of the pivoted frame opposite that on which the printing member is arranged and being connected to the feed member to effect the operation of the feed member after the printing operation.
4. In a printing machine, the combination with a platen, a frame pivotally mounted with relation to the platen, a rotary printing member mounted to turn about an axis transverse of the turning axis of the

pivoted frame and upon one side of said turning axis, of a variable work-feeding mechanism for moving the work relatively to the platen after the printing operation embodying a feed member and a rotary gage, the rotary gage being mounted on the shaft of the rotary printing member upon the side of the axis of the pivoted frame opposite that on which the printing member is arranged, and a spring-pressed cam member coöoperating with the gage member and having a pawl and ratchet connection with the feed member.

5. In a printing machine, the combination with a platen, a frame pivotally mounted with relation to the platen, and a printing member mounted to turn about an axis transverse to the turning axis of the pivoted frame and upon one side of the latter turning axis, of a variable work-feeding mechanism comprising a rotary feed member, a swinging member carrying a pawl, a ratchet engaged by said pawl and connected to the rotary feed member, a rod eccentrically pivoted to the swinging member, a pivoted cam having the rod eccentrically connected thereto, a rotary gage mounted on the shaft of the rotary printing member on that side of the axis opposite to that on which the printing member is mounted, and a spring acting on the cam member to hold the latter in coöoperative relation with the gage member.

6. In a printing machine, the combination with a platen and a printing member movable relatively to each other for effecting the printing operation, the printing member also being adjustable to position any type thereon over the printing point, of a variable work-feeding mechanism embodying a feed member, a gage member, the gage member having two movements one of which is controlled by the printing member when the latter is adjusted to position the type over the printing point and the other of which is controlled by the relative movement between the platen and the printing member during the printing operation, a member arranged to be engaged by the gage member upon the second movement of the latter, said member having a ratchet connection with the feed member, and a spring acting on said member to hold the latter toward the gage member.

7. In a printing machine, the combination with a frame having a base portion and a portion overhanging the base portion from one side of the latter to provide a space between them, of a platen carried by the base portion, a printing wheel carried by the overhanging portion, means for effecting a relative movement between the platen and the printing wheel to cause the printing action, and a variable work-feeding mechanism comprising a feeding wheel arranged on the

base portion of the main frame, and a rotary gage member for determining the position of the feeding member mounted to turn about an axis transverse to the turning axis of the rotary feed wheel and arranged in that portion of the main frame to one side of the space between the base and the overhanging portion.

8. In a printing machine, the combination 10 with a platen and a printing member movable relatively to each other for effecting the printing operation, the printing member also being adjustable to position any type thereon over the printing point, of a variable work-feeding mechanism embodying a feed member, a gage member having two movements, one of which is controlled by the printing member when the latter is adjusted to position the type over the printing 20 point and the other of which is controlled by the relative movement between the platen and the printing member during the printing operation in order to effect the movement of the feed member after the printing 25 operation, and locking means for said gage member embodying two parts, one carried by the gage member and the other being stationary and adapted to be engaged by the part on the gage member when the latter is 30 moved to effect the printing operation.

9. In a printing machine, the combination 35 with a main frame embodying a base portion and an overhanging portion, of a frame pivoted to the overhanging portion, a rotary printing wheel mounted to turn upon the pivoted frame about an axis extending transversely of the pivotal axis of the pivoted frame, said printing wheel having words or expressions thereon extending in 40 lines parallel to the turning axis of the wheel, and a variable work feeding mechanism for feeding the work in the direction of the axis of turning of the printing wheel.

10. In a printing machine, the combination 45 with a main frame embodying a base portion and an overhanging portion supported from one side of the base portion, of a rotary printing wheel mounted to turn about an axis which intersects the supporting portion of the overhanging portion, said printing wheel having words or expressions thereon extending parallel to each other and to the turning axis of the wheel, and a variable work-feeding mechanism for feeding 55 the work in the direction of the axis of turning of the printing wheel.

11. In a printing machine, the combination 60 with a main frame embodying a base portion and an overhanging portion supported from one side of the base portion, of a platen carried by the base portion, a frame pivotally supported on the overhanging portion, a rotary type wheel mounted to turn on the frame about an axis extending trans- 65 versely of the turning axis of the pivoted

frame, the shaft of the type wheel being extended to the supported part of the overhanging portion, a flanged member on said shaft, a rotary feed wheel arranged on the base portion of the main frame, and a pivoted 70 cam member having a ratchet connection with the rotary feed wheel and adapted to be engaged by the rotary flanged member to be shifted by the latter when the pivoted frame is moved to carry the printing 75 wheel toward the platen.

12. In a printing machine, the combination 80 with a platen, a pivotally mounted frame movable toward and from the platen, and a printing member carried by said frame, of a work feeding mechanism embodying a rotary feed wheel, and clamping means for coöperating with said feed wheel comprising a spring-pressed clamping member 85 and an operating member for coöperating with the clamping member; said operating member being mounted to turn about an axis common to the turning axis of the pivoted frame.

13. In a printing machine, the combination 90 with a frame having a base portion and a portion overhanging the base portion from one side of the latter to provide a space between them, of a platen carried by the base portion, a printing mechanism carried by 95 the overhanging portion, means for effecting a relative movement between the platen and the printing mechanism to cause the printing action, a work-supporting surface surrounding the platen, and feeding mechanism 100 for moving the work relatively to the printing mechanism in a line extending toward the inner or supported end of the overhanging portion, said feeding mechanism embodying two coöperating rollers, one arranged above the work supporting surface 105 and the other projecting through the work supporting surface.

14. In a printing machine, the combination 110 with a frame having a base portion and a portion overhanging the base portion from one side of the latter to provide a space, of a printing mechanism carried by the overhanging portion and having its line of printing 115 extending toward the inner or supported end of the overhanging portion, a work supporting surface carried by the base portion, a gage at the outer end of the work supporting surface, said gage extending transversely of the printing line and being 120 adjustable in the direction of the line of printing, and a feeding mechanism embodying two coöperating rollers, one arranged above the work supporting surface and the other projecting through the work supporting surface.

15. In a printing machine, the combination 125 with the platen and a printing member, one of which is movable toward and from the other to effect the printing operation, of 130

- a work supporting plate entirely surrounding the platen and formed from sheet metal having opposite edges bent to form guides on the under side thereof, and an extension plate for supporting the work during printing, adjustable on said guides.
16. In a printing machine, the combination with a platen and a printing member, one of which is movable toward and from each other to effect the printing operation, of a work supporting surface entirely surrounding the platen, guiding means parallel with the line of printing, and a work supporting extension movable on said guiding means.
17. In a printing machine, the combination with a platen and a printing member, one of which is movable toward and from each other to effect the printing operation, of a work supporting surface entirely surrounding the platen, guiding means parallel with the line of printing, and a work supporting extension movable on said guiding means and having a gage for the work.
18. In a printing machine, the combination with a frame having a base portion and an overhanging portion, of a printing member arranged on the overhanging portion, a platen arranged on the base portion, one of the last two named parts being movable toward and from the other to effect the printing, a work-supporting surface on the base portion entirely surrounding the platen, means for feeding the work between the platen and the printing member, and work-supporting extensions for said surface arranged on opposite sides of the line of feed.
19. In a printing machine, the combination of a platen, a type wheel and a work feeding gage adjustable to set the type and to determine the extent of the feed, means for effecting a printing relative movement of the type wheel and platen and a work feeding movement of the gage, a work feeding element variably rotatable in engagement with the work to feed the work between the type wheel and the platen, and devices cooperating with the gage whereby the feeding movements of the gage will effect variable rotations of the feeding element.
20. In a printing machine, the combination of a platen, a printing wheel having type forms of different lengths thereon, the printing wheel being adjustable to set any desired form opposite the platen and the wheel and platen having a relative printing movement, a work feeding element to be variably rotated in engagement with the work to feed the work varying distances between the printing wheel and platen, a work feeding gage adjustable with the printing
- wheel to determine the length of feed and given a work feeding movement when the printing wheel and platen are operated to print, and devices cooperating with the gage whereby the feeding movements of the gage will effect rotation of the feeding element distances depending upon the adjustment of the gage.
21. In a printing machine, the combination with a platen, of a frame mounted for movement relative to the platen, a type wheel and a work feeding gage adjustably supported by the frame, a feeding element variably rotatable in engagement with the work to feed the work between the type wheel and platen, means for moving the frame to bring the type wheel and platen together to print, and devices controlled by the gage whereby said movements of the frame will effect the variable rotations of the feeding element.
22. In a printing machine, the combination with a stationary platen, and a printing wheel having a plurality of parallel lines of type thereon of different lengths, of a shaft by which said wheel is carried, said shaft being movable laterally to carry the wheel toward the platen, a gage member having a plurality of shoulders thereon corresponding to the lines of type on the printing wheel, said gage member being arranged on the shaft to turn with the latter and also to be shifted when the shaft is shifted laterally, and a variably rotatable member controlled by the gage for feeding the work over the platen.
23. In a printing machine, the combination with a movable support, a shaft rotatably mounted in said support, a type wheel having a plurality of lines of type of different lengths thereon, a gage having shoulders of different lengths corresponding to the lengths of the type lines on the type wheel, said wheel and gage being secured to the aforesaid shaft near the opposite ends thereof, a stationary platen, an operating handle for first rotating the shaft to set the type wheel and gage and then moving the support to carry the type wheel against the platen to print, a spring for moving the support in the opposite direction to carry the wheel away from the platen, and a variably rotatable work feeding element rotated in engagement with the work during movement of the type carrier away from the platen to feed the paper between the type carrier and platen varying distances determined by the setting of the gage.

CHARLES H. SAMPSON.
